UNITED STATES PATENT OFFICE.

ERIC J. WAHLBERG, OF FORT BRAGG, CALIFORNIA, ASSIGNOR TO ATLAS TANK MANUFACTURING COMPANY, OF FORT BRAGG, CALIFORNIA, A CORPORATION OF CALIFORNIA.

MOUNTING FOR SILO-DOORS.

1,221,779.

Specification of Letters Patent.

Patented Apr. 3, 1917.

Application filed October 24, 1916. Serial No. 127,401.

To all whom it may concern:

Be it known that I, ERIC J. WAHLBERG, a citizen of the United States, residing at Fort Bragg, in the county of Mendocino and 5 State of California, have invented new and useful Improvements in Mountings for Silo-Doors, of which the following is a specification.

This invention relates to silo doors, and 10 has for its object to provide a simplified and improved mounting therefor.

Silo doors ordinarily do not have hinges but work in vertical guides and are generally removed bodily on emptying the 15 contents of the silo. This is objectionable on account of the possibility of breaking the doors and misplacing the same. A hinge mounting is desirable for this purpose and the hinge should be placed on the outside 20 where it will not be contacted by the ensilage and yet permit the door to swing inwardly and rest flatly against the inside of the silo. The hinge must be small and compact and not project in such way as to obstruct the 25 ladder which is formed across the vertical opening or doorway.

One form which my invention may assume is exemplified in the following description and illustrated in the accompanying drawings, in which:—

Figure 1 shows a side elevation of a portion of a silo embodying my invention.

Fig. 2 shows a sectional view of the same on the line 2—2 of Fig. 1.

Fig. 3 shows a perspective view of the hinge mounting detached.

In the drawings I show a silo 10 having a vertical opening or doorway 11 and a series of door sections 12 for closing said openings. 40 The door sections rest against the inside faces of vertical side jambs 13 and horizontal cross-jambs 14, and each door or section has cleats 15 near its top and bottom ends carrying ladder runs 16.

The hinge mounting is so constructed as 45 to nest in the corner of the doorway between the cleats 15, and comprise a pair of vertically spaced straps 20 screwed or bolted to one of the side jambs 13 and forming bearings or supports for journal pins 21 to which cross-arms 22, formed integrally on the ends 50 of a vertical supporting member 23, are connected. Connecting pivotally with the opposite ends of the cross-arms 22, by means

of pins 24, are swinging links 25 having 55 pivotal connections at their opposite ends by means of pins 26 with straps 27 secured to the adjacent end of the door at the outer face thereof.

By making the arms 22 and links 25 comparatively short, and folding them in V shaped relation, I avoid any obstruction of the ladder runs 16 and yet obtain sufficient movement of the parts to permit the door to swing inwardly clear of the doorway and rest with its inner face engaging the side of the silo. The arms 22 are slightly longer than the links 25 and are adapted to project through the doorway when the door is open and engage the edge of the side jamb, 70 projecting just far enough beyond the inner face of the jamb to permit the links 25 to swing to one side with the door, and allow the adjacent edge of the door to fit in the angle or corner formed by the links 25 and 75 arms 22. The vertical connection between the arms 22 is preferably reinforced by a rib 28 and affords an improved support for the door.

Having thus described my invention, what 80 I claim and desire to secure by Letters Patent is:—

1. A hinge for silo doors composed of a vertical member having a cross arm on each end thereof, jamb straps pivotally connected 85 with one end of each respective cross arm, links pivotally connected at one end with the respective other ends of the cross arms, and door straps pivotally connected to the other respective ends of the swinging links, 90 said member in open position of the door being engageable with the inner side edge of the jamb.

2. A hinge for silo doors composed of a vertical member, jamb straps pivotally connected with the respective ends of said member, links also pivotally connected at one end with the respective ends of said member, and door straps pivotally connected to the opposite respective ends of the links. 100

In testimony whereof I have hereunto set my hand in the presence of two subscribing witnesses.

ERIC, J. WAHLBERG.
